UNITED STATES PATENT OFFICE.

ARTURO F. MOELLER, OF SAN PEDRO, MEXICO.

BEATER.

Application filed May 8, 1924. Serial No. 711,847.

To all whom it may concern:

Be it known that I, ARTURO F. MOELLER, citizen of Mexico, residing at San Pedro, Coah., Mexico, have invented certain new and useful Improvements in Beaters, of which the following is a specification.

This invention relates to an improved beater for beating eggs, whipping cream or the like, and seeks, among other objects, to provide a device of this character which will accomplish the beating operation quickly and efficiently with a minimum of effort.

The invention seeks, as a further object, to provide a device which will successfully combine extreme structural simplicity with functional superiority.

And the invention seeks, as a still further object, to provide a beater which may be readily assembled and as easily taken apart for cleaning.

Other and incidental objects will appear hereinafter.

In the drawings:

Figure 1 is a vertical sectional view through my improved beater,

Figure 2 is a bottom plan view of the dasher head employed,

Figure 3 is an enlarged detail sectional view showing the mounting of the bottom plate of the dasher head, and

Figure 4 is a fragmentary sectional view illustrating a slightly different embodiment of the invention employing a glass receptacle.

In its preferred embodiment, the device is preferably formed entirely of aluminum and includes a cylindrical receptacle 10 rolled at its upper edge to form a surrounding bead 11 while at one side thereof, the receptacle

is equipped with a handle 12 suitably secured to the wall of the receptacle. Closing the receptacle is a removable cover 13 from which is pressed an annular bead 14 to rest against the bead 11 of the receptacle

and depending from the bead 14 is an annular flange 15 snugly fitting in the receptacle. At the top thereof, the cover is formed with a cone-shaped basin 16 terminating at its apex in a guide flange 17 disposed axially

of the cover as well as the receptacle and freely slidably through said flange is a dasher rod 18. At its upper end, the rod is looped to form a handle 19 and screwed upon the lower end of the rod is a nut 20

providing a stop shoulder. Removably connected with the rod at its lower end is a

conoidal shell or head 21, the wall of which is closely apertured substantially throughout its area and, as will be observed, the shell is truncated to receive the rod through the upper end thereof. Resting upon the upper end edge of the dasher head to about the nut 20, is a washer 22 freely accommodating the rod therethrough and screwed upon the lower end of the rod within the head is a nut 23 tapered to fit the head seating flat against the wall thereof. Thus, after the nut 23 has been applied to the rod, the nut may be held stationary with one hand, when, by turning the rod with the other hand, the head may be tightly clamped upon the rod. Closing the head or shell at its lower end is an appropriate bottom plate 24 provided at one side thereof, as shown in Figure 2 of the drawings, with a notch 25 and struck from the lower margin of the head is a plurality of inwardly turned lugs 26 supporting the plate, the lugs being preferably three in number and being equally spaced about the periphery of the head. As brought out in Figure 3, the lugs sustain the plate to slightly wedge at its periphery within the dasher head so that the plate is thus held stationary. However, by turning the plate until the notch 25 thereof is brought opposite one of the lugs 26, the plate may be swung downwardly at its adjacent side and removed, while by reversing the operation, the plate may be as easily installed. Thus, as will be seen, the plate may be readily detached from the dasher head while the head may be easily detached from the dasher rod when, by removing the nut 20, the rod may be detached from the cover 13. Accordingly, the device may, without difficulty, be quickly taken apart for cleaning.

In use, egg white, for instance, is placed in the receptacle 10 and the cover 13 applied, when the handle 19 is grasped and the dasher rod rapidly reciprocated. The egg white will thus be forced through the openings in the plate 24 into the dasher head and through the openings in the head with the result that the egg white will be quickly beaten to a stiff mass, when the cover and dasher may be displaced for removing the beaten mass from the receptacle. Any of the egg sticking to the rod 18 will be collected in the basin 16 so that waste of the egg or smearing of the cover 13 therewith will be obviated. As will be noted, the open-

ings in the head 21 are smaller than the openings in the plate 24. I have found this feature to be of advantage when the device is designed for use as an egg beater. To obtain the best and quickest results, the egg white must, as the head 21 is reciprocated, enter the head rapidly through the plate 24 and the plate is accordingly provided with relatively large openings, while by restricting the egress of the egg white through the wall of the head, air is caused to be mixed with the egg white as it is forced through the small holes of the head at each downward stroke of the head. However, by varying the size of the openings in the parts 21 and 24 and the relative proportion thereof, the device may be readily adapted for use in whipping cream or mixing other fluids.

In Figure 4 of the drawings, I have illustrated a slightly different embodiment of the invention, wherein I employ a glass receptacle 27. This receptacle is preferably of the same shape as the receptacle 10 and is open at the upper end thereof to receive a cover 28. The cover 28 is identical with the cover 13 with the exception that the cover 28 is provided with a depending annular flange 29 to fit over the upper end of the glass receptacle. Otherwise, the embodiment of Figure 4 of the drawings is identical with the preferred embodiment of the invention and further description is accordingly believed unnecessary.

Having thus described the invention, what I claim is:

1. In a device of the character described, a dasher including a dasher rod, a foraminous dasher shell connected with the rod, and a removable foraminous bottom plate nor-

mally closing the shell and removable without disturbing the connection between the shell and rod.

2. In a device of the character described, a dasher including a dasher rod, a cone shaped foraminous dasher shell connected at its smaller end with the rod, and a removable foraminous bottom plate carried by the shell near its larger end and removable without disturbing the connection between the shell and rod.

3. In a device of the character described, a dasher including a dasher rod, a foraminous dasher shell, means rotatably adjustable upon the rod and clamping the shell thereon, and a foraminous bottom plate carried by the shell.

4. In a device of the character described, a dasher including a dasher rod, a cone shaped foraminous dasher shell connected at its smaller end with the rod and provided at its larger end with inwardly directed lugs, and a foraminous bottom plate resting on said lugs closing the shell at its larger end, the bottom plate being provided with a notch to freely accommodate one of said lugs therethrough whereby the bottom plate may be removed.

5. In a device of the character described, the combination of a dasher rod, a dasher shell carried thereby and provided throughout the major portion of its area with a multiplicity of closely spaced substantially uniform small openings, and a bottom plate for the shell provided with a plurality of openings larger than the openings of the shell.

In testimony whereof I affix my signature.

ARTURO F. MOELLER. [L. S.]
